UNITED STATES PATENT OFFICE

1,969,312

STRUCTURAL UNIT

Stanley Macomber, Edgefield District, Ohio

Application September 29, 1930, Serial No. 485,183

6. Claims. (Cl. 189—37)

My invention particularly relates to a light truss-like structure adapted for use instead of beams in carrying light loads as in the case of joists in floors and the like; and may also be advantageously employed as a column, as a roof purlin, and as a reinforcement for concrete floors. A further object is the provision of a structural unit of this type wherein end members are provided having continuous supporting surfaces in order to secure flexibility, or in other words permit variation in the span lengths for which any particular truss can be used. Still another object is to provide in such a structural unit for variation in the span length, or in other words an extension of the normal length of the span using the same elements and thus avoiding additional cost in the manufacture of separate trusses of different lengths. Still another object is to provide joist end pieces which will permit the use of a net span joist end for a plurality of spans by the use of additional strengthening members connecting the ends of the web and the bottom chord and end pieces, a standard web being utilized for such series of joists, the length of top and bottom chords being varied for each individual joist of the series. Various illustrative forms of the constituent elements of my improved unit are hereinafter fully described and also shown in the accompanying drawings.

The invention is an improvement particularly of the structure shown, described and claimed in U. S. Patent No. 1,651,032, of November 29, 1927, issued upon my improvements in Structural units. In the invention of that patent I present a structural unit which has all the advantages as to the economy of metal inherent in a truss type of structure and at the same time is not subject to the objections in a truss of lack of flexibility in the matter of the distance apart of the points of support, these disadvantages being obviated by the use in the unit of beam ends which afford a multiplicity of points of support for the whole unit and are tied into the central truss portion so as to adapt the unit as a whole to sustain a predetermined load irrespective of the points of support within the minimum and maximum spans for which the unit is designed.

50. The improvements in the construction shown in this instant application over the invention shown in said patent reduce the cost of labor and material entering into the production of units of this general character; afford somewhat more standardization of the constituent

parts entering into the different units by permitting a wider field of use of standard portions of the units; and simplify somewhat the field work incident to installation.

The annexed drawings and the following description set forth in detail certain means embodying my invention, such disclosed means constituting, however, only a few of the various forms in which the principle of the invention may be illustrated.

In said annexed drawings:

Figure 1 is a side elevation of a complete structural unit embodying one form of end piece adapted to co-operate with the central truss portion to produce the complete unit of the desired character and advantages;

Figure 2 is a side elevation, upon an enlarged scale, of one end of the unit shown in Figure 1;

Figure 3 is a plan view of the unit end shown in Figure 2;

Figure 4 is a bottom plan of the unit end shown in Figures 1 and 2;

Figure 5 is a vertical section, taken in the plane indicated by the line 5—5, Figure 2;

Figure 6 is a horizontal section, taken in the plane indicated by the line 6—6, Figure 2;

Figure 7 is a perspective view of the form of unit end piece shown in the preceding figures;

Figure 8 is a side elevation, upon the same scale as that of Figure 2, of a second form of truss end;

Figure 9 is a plan view of the truss end shown in Figure 8;

Figure 10 is a vertical section, taken in the plane indicated by the line 10—10, Figure 8;

Figure 11 is a horizontal section, taken in the plane indicated by the line 11—11, Figure 8;

Figure 12 is a vertical section, taken in the plane indicated by the line 12—12, Figure 8;

Figure 13 is a side elevation of a third form of truss end;

Figure 14 is a plan view of the end-piece shown in Figure 13;

Figure 15 is a vertical section, taken in the plane indicated by the line 15—15, Figure 13;

Figure 16 is a horizontal section, taken in the plane indicated by the line 16—16, Figure 13;

Figure 17 is a vertical section, taken in the plane indicated by the line 17—17, Figure 13;

Figure 18 is a side elevation of a fourth form of truss end;

Figure 19 is a plan view of the truss end shown in Figure 18;

Figure 20 is a vertical section, taken in the plane indicated by the line 20—20, Figure 18;

Figure 21 is a horizontal section, taken in the plane indicated by the line 21—21, Figure 18;

Figure 22 is a side elevation of a complete structural unit utilizing the form of truss-end shown in Figure 13, this unit being adaptable for a series of spans, and the web-member of the unit consisting of three connected parts, a central portion and two end portions, of which the end portions are of somewhat heavier material 10 per unit length than the central truss portions;

Figure 23 is a view similar to Figure 22 of a complete structural unit, utilizing the net span end shown in Figure 18, this unit being adaptable for one span only;

Figure 24 is a view similar to Figure 23 in which the same end piece as that shown in Figure 23 is utilized but the span adapted to be served by the unit is somewhat longer than the span served by the unit shown in Figure 23, the 20 web-members of Figure 24 being reversed in positions from those shown in Figure 23, the chord members being somewhat longer in Figure 24, and additional end web extensions being shown in Figure 24 connecting the ends of the reversed 25 web-members and the bottom ends of the end pieces and the outer ends of the bottom chord member;

Figure 25 is a detailed illustration of certain 30 end web extensions which will serve as the additional end filling members between the webs and the end pieces for a series of joists adapted to serve varying spans and utilizing the same web-members and end pieces;

Figure 26 is a side elevation of substantially 35 one-half of a structural unit adapted to serve a span somewhat greater than that served by the unit of Figure 24 by the use of a different end filling member than that shown in Figure 24 and somewhat longer chord-members, together with 40 the same web-members and end pieces as those shown in Figure 24;

Figure 27 is a side elevation of the end of a truss in which T sections are used for the chord-members;

Figures 28 and 29 are vertical sections, taken 45 in the planes indicated by the lines 28—28 and 29—29, respectively, Figure 27;

Figure 30 is a vertical section, similar to Figure 28, of a unit in which plain plates are 50 used as chord-members;

Figure 31 is a side elevation of the ends of a unit in which double T sections are used for chord-members;

Figures 32 and 33 are vertical sections, taken, 55 respectively, in the planes indicated by the lines 32—32 and 33—33, Figure 31;

Figure 34 is a section, similar to Figure 32, of a unit in which two plain angles are used for each of the upper and lower chord-members;

Figure 35 is a side elevation of a unit in which 60 a split rail is utilized for the upper and lower chord members;

Figures 36 and 37 are vertical sections, taken, 65 respectively in the planes indicated by the lines 36—36 and 37—37, Figure 35; and

Figures 38 and 39 are side elevations of the 70 ends of units which have somewhat modified end structures from those previously shown, and which will hereinafter be described in detail, these different details of ends being utilized either with the T or the double T section, the 75 particular embodiments herein shown being the double T in Figure 38 and the single T section in Figure 39.

Referring to the annexed drawings in which

the same parts are indicated by the same respective numbers in the several views, all of the forms of structural units shown in these drawings consist primarily of a central truss portion combined with strengthening and stress-transferring supporting ends interlocked with the truss center so as to withstand the support reactions and to co-operate with the truss center to form an integral unit adapted to give the desired service. In the first three of the several forms illustrated in the drawings, Figures 1 to 17, inclusive, these supporting ends are extended and so interlocked with the truss center as to provide a plurality of points of support, or continuous supporting surfaces for a material distance, whereby one unit will serve for any desired span of a plurality of spans, thus obviating the necessity of making an entirely separate unit for each span and thus permitting a comparatively small number of different units to serve for a comparatively large number of different spans. As hereinafter fully described, the fourth form of the invention shown in Figures 18, 19, 20, and 21, is designed for a single net span, but most of the component parts of this net span unit are comprised of standard elements and only slight changes of a nature comparatively easily made permit the production of different net span units to serve the spans necessitated by the specifications of 105 different jobs within a given range of spans. The central truss portion of the units is comprised of a top chord member and a bottom chord member combined with a connecting web member, the particular form of truss illustrated 110 in these figures being the well-known Warren truss and having parallel twin bars 1 and 2 comprising the upper chord, and parallel twin bars 3 and 4 comprising the lower chord and suitably spaced from the upper chord, and an 115 intermediate connecting continuous and reversely bent bar 5 serving as the web, this web being rigidly secured at its bends intermediate the twin-bar upper and lower chords, preferably by welded joints 8 and 9. Preferably, the 120 web-member consists of a central portion and two end portions connected at their inner ends to the ends of the central portion and formed of material of greater weight and gauge per unit length than the central portion. Figures 125 22 and 23, 24 and 26 show the web-member so constructed of different connected elements and these elements will be hereinafter fully described in connection with the description of the units shown in said figures. Figures 27 to 39, 130 inclusive, show modified chord and truss structures and some detailed end-piece variations 135 adaptable for units containing the improvements of the invention.

Referring particularly to the form of the invention shown in Figures 1 to 7, inclusive, the unit supporting-end extension which may be a casting comprises a base 11 and a vertical strengthening member 10 extended at right angles to the base 11 and formed at its inner end with an inwardly and downwardly projecting portion 10', the base 11 being formed with a similar inner end portion 11', the inner bottom end of this combination support and strengthening member being integrally secured to the end web member 6, preferably by a welded joint 7. Inasmuch as the stresses which the members 10' and 11' must withstand decrease in amount from the downward bend of the members 10—10' and 11—11' to the joint 150

thereof with the web member 6, these members 10' and 11' graduate in width from top to bottom, as is clearly shown in Figure 5. Upon the top of the member 10 is a horizontal plate 12 which gradually increases in width from the outer end of the unit end to substantially the inner end of the vertical plate 10, as clearly shown in Figures 3 and 7. The ends of the twin-bar upper chord 1-2 are rigidly secured 10 to the sides of the plate 10 adjacent the inner end of the latter, preferably by welded joints 16, the inner edge of the top plate 12 forming a stop 13 against which the outer ends of the bars 1 and 2 rigidly abut. The bottom end of the member 10' is formed with a horizontal outwardly-projected extension 14, Figure 6, against the sides of which the ends of the twin-bar bottom chord 3-4 are rigidly secured, preferably by welded joints 15, Figure 4.

In the form of invention shown in Figure 8 to 12, which may be of forged steel construction, the vertical strengthening plate 17 having an inward and downward end portion 17' is rigidly secured to supporting base angles 18 and 19 having inner and downwardly projecting end portions 18' and 19', and the extending end portions 18' and 19' terminating somewhat short of the bottom of the member 17' where the stresses to be withstood are so comparatively slight as to make unnecessary any further extension of such strengthening members 18' and 19'. In this form of device the ends of the top twin bars 1 and 2 are welded by joints 21 to the sides of the inner end of the vertical plate 17 and the ends of the twin bottom bars 3 and 4 are welded by joints 20 to the sides of the inner end of the downwardly extending plate portion 17'.

In the form of device shown in Figures 13 to 17, inclusive, the unit end piece comprises a vertical plate 26 secured by welded joints 28 to a relatively right angular base plate 27, the latter having a short inwardly and downwardly extended end portion 27'. In this form of construction the connecting stress-transferring member between the upper supporting extension and the bottom truss chord consists of a bent bar having portions 29, 30, and 31, clearly shown in Figure 13, which form an endless band by reason of the welded joint 35 connecting the bottom of the members 29 and 31, as clearly shown in Figure 13, the bar member 29 being secured to the downwardly extending plate member 27' by a welded joint 33 and also being secured to the inner edge of the vertical strengthening plate 26 by a welded joint 34. In this form of construction the twin bottom bars 3 and 4 are secured by welded joints 37 to an outwardly extended horizontal end portion 32 of the bar member 29. The bottom of the end web member 6 is secured to the bottom of the bar 31, between the bottom chord bars 3 and 4, by a welded joint 36.

a series of units utilizing such an end piece so that only slight changes which can be conveniently and economically made permit the designing of the same kind of net span unit for various net spans. For the joist utilizing the end piece shown in Figure 18, I utilize a web having a standard number of bends and a standard bend angle. I also utilize supporting base members 42, suitable for mounting upon columns or walls, separated by a net span, a vertical strengthening plate 41 being secured to the base 42 by welded joints 43. The inner end of the base 42 is inwardly and downwardly extended to form a connecting member 42' to which a bar 44 is secured by a welded joint 48, this bar 44 having an upper and inwardly extending end member 45 secured to the front edge of the vertical strengthening plate 41 by a welded joint 47, the bottom end of the bar 44 being secured to the end of the web member 6 and between the twin bar bottom chord members 3 and 4 by welded joints 49. The bottom end of the bar 44 is bent into an extended horizontal connecting member 46 for the rigid securing of the ends of the bottom chord bars 3 and 4 by welded joints 50. When an end piece, such as has been just described, is incorporated with a web-member and suitable chord members, it will serve in a joist intended to bridge the minimum span that would be served by a joist having the standard end piece shown in Figure 13 and having the same web-member and chord members as are utilized with the net span end piece shown in Figure 18. However, if spans greater than the minimum span adapted to be served by a joist having a standard end piece, such as shown in Figure 13, are to be served by joist having net span end pieces, and adapted for service within the series of spans served by the end piece of Figure 13, then some changes are necessary in the combination of elements comprising the joist, and such changes will now be described in detail.

Referring particularly to Figures 22 to 26, inclusive, it is presumed that Figure 22 represents a certain joist having standard span ends furnishing a multiplicity of supports and incorporated with the truss center so as to be capable of serving for any desired span of a plurality of spans. Figure 23 illustrates a joist having net span ends and capable of serving the minimum span which can be served by the joist shown in Figure 22. If it is desired to bridge a span between the minimum and maximum spans served by the joist shown in Figure 22, and still utilize a net span end, this can be done by a slight reorganization of the joist which will entail somewhat extra labor but, by reason of the saving of the material, will be an economy, if at least a minimum number of joists of this same specification are needed. This reorganization is effected by reversing the

The three forms of the invention hereinbefore described permit the use of each of these end pieces for a plurality of spans by reason of the extended reinforced bases or end supporting members and the nature of the connections between the units truss center and the reinforced supporting ends. In the form of device shown in Figures 18 to 21, inclusive, the structure is such as to permit the use of the end piece for only a net span, unless some changes are made in the unit as a whole, as hereinafter fully described. However, several standard elements enter into the web 53 shown in Figures 22 and 23 in the manner shown in Figure 24. The upper and lower chords 55 and 56 are lengthened out, in accordance with the span for which the joist is specified, the net span end pieces are moved out the necessary distance and the space between the bottom of the bar 44 of the net span end and the top 54 of the reversed end web-member is filled by an additional end web extension 57 which is secured top and bottom between the twin bars of the top chord 55 and the bottom chord 56, at the joints where the 140 145 150

- end web-member and the bar 44 are secured between these twin-bar chords. Thus it will be seen that, by reversing the web and lengthening out the chords and using an additional filling bar, the same web-member and the same net span end pieces can be utilized for any desired span between the minimum and maximum spans served by the corresponding joists having the standard span end pieces. What is meant by "lengthening out the chords" is that other upper and lower chords of suitable length for the increased span are utilized instead of the chords which are suitable for the minimum span. In other words, the increased span is accommodated by the same web-member, in reverse position, and the same net span end pieces, as accommodated the lesser span, and the only new elements are the chords of suitably greater length and the suitable end web extension.
- The additional end filling bars are several in number for the various spans between the minimum and maximum spans of the corresponding standard end joist. Assuming, for instance, that the variation between the minimum and maximum span is 11 inches, then 3 such bars would serve for the entire differential, such bars being illustrated in Figure 25. For purposes of illustration, it might be assumed that bar 57 would serve for an increase of from $\frac{1}{2}$ inch to $2\frac{1}{4}$ inches over the minimum span at each end of the joist; bar 58 would serve for increases from $2\frac{1}{2}$ to 4 inches at each end of the joist; and bar 59 would serve for increases from $4\frac{1}{4}$ to $5\frac{1}{2}$ inches at each end of the joist. Of course, a 12-inch differential in span would amount to 6 inches at each end of the joist. If the increased span is 6 inches or more at each end, then the joist of the next series would be utilized, either a joist for the entire series having standard span ends, or a joist having net span ends and filling bars, if the increase in span is not a foot or a multiple of a foot, by reversing the web and using the proper additional end filling bar. In Figure 26, it is assumed that the increase at each end has been so great as to make necessary the use of the filling bar 59 which is the bar utilized for the higher spans of a series, when using net span ends.
- There are some suggestions in Figure 25 of the approximate sizes of a series of end web extensions and the proper angles at which they can be utilized for different spans of a series of spans. It is assumed, for instance, that the three bars shown in Figure 25 will serve for the series of spans which would be served by a joist of the character shown in Figure 22, if net span ends, such as shown in Figure 23, were utilized instead of standard span ends. Of course, for the minimum span, no one of the bars shown in Figure 25 would be used because the joists are so designed that for this minimum span the net span ends only will serve, and the web-member is utilized in its normal position and not reversed as is the case when the joist is utilized for the greater spans and one of the filling bars 57, 58, or 59 is used.
- It is preferable to subdivide the web-member into three sections, a central section 51, and two end sections 52 which are integrally connected between the top and bottom chord members to the respective ends of the central web-member 51. Because of the stresses which they respectively withstand, the end web-members 52 are of somewhat greater weight and gauge per unit length than the central web-member 51, and they are so shown in the accompanying drawings, Figures 22, 23, 24, and 26. In the reversed web-member construction shown in Figure 24, the end web-members of larger gauge are indicated by the number 54.
- Referring particularly to Figures 27 to 39, inclusive, in which various modifications of chord structures and unit-end structures are shown, for the purpose of illustrating some of the possible variations coming within the principle of my improvements, I show in Figures 27, 28, and 29 a unit-end in which T-sections 61 are utilized as top and bottom chords. The vertical end plate 26 is secured by welded joints 62 to the bottom of the ends of the top chord 61, this chord being extended outwardly substantially to the end of the unit supports. A bent end bar 29-30-31, such as shown in Figure 13, is secured by welded joint 63 at the top to the bottom of the upper chord 61 and by welded joints 64 and 66, respectively, to bottom chord 61 and to the end web-member 6. The web-member is secured by welded joint 65 to the top of the bottom chord 61 and by welded joint 67 to the bottom of the upper chord 61.
- Figure 30 illustrates the use of plain plates 68 as chord-members to the respectively opposed faces of which the top and bottom of the web-member 5 is secured by welded areas 69 and 70, respectively.
- In Figures 31, 32, and 33, I have illustrated the use of double T-sections 71 for chord-members, between the opposed webs 72 of which the vertical end plates 26 are secured by welded area 73, and the end bar 29-30-31 is secured by welded area 73², and the web-member is secured by welded area 73.
- In Figure 34, I have illustrated the use of two plain angles 74 as chord-members, between which the associated elements of the unit are secured, as illustrated by the welded areas 75 by means of which the web-member is secured to the chords.
- Referring to Figures 35, 36, and 37, I show a split rail comprised of the upper member having the flange 76 and the web 78 and the lower member having the flange 77 and the web 79, which are utilized for the top and bottom chords. The securing of the associated elements to the chord-members by welded areas is similar to that illustrated in Figure 27.
- Figure 38 shows an end-piece, modified in details, particularly as regards the shape of the vertical end plates 80 and the connection thereof with the bent end bar 29-30-31. I have illustrated this end-piece as associated with double T chord-members 71 between the webs 72 of which the vertical end plates 80 are secured, as also the bent bar 29-30-31, and the angles of the web-member. The end plates 80 are cut square at the ends and the inner end thereof is secured to the bent end bar 29-30-31 by the welded area 83. The underlying supporting base of the end-piece is formed by a horizontal plate 81 to which the bottom of the vertical plates 80 are secured by welded areas 82, this plate 81 having an inwardly and downwardly extended end portion 81' to which the member 29 of the bent bar is secured by welded areas 84.
- In Figure 39, I have illustrated a modified end structure in which single T-sections are utilized as chord-members, the modification consisting principally in extending the outer member 88 of the bent bar 88-89-90 vertically downward-

ly, and the inner member 90 thereof outwardly as well as downwardly, and in securing the end web-member 91 to the top of the bar member 90 instead of to the bottom, as is true of the 5 web-member connections heretofore shown with this general type of end-piece. The supporting end base 86 is secured to the vertical plate 85 by welded areas 87, and has a downwardly extended vertical end extension 86' secured to the 10 bar member 88 by welded area 92, this bar member 88 being also secured to the inner edge of the vertical plate 85 by welded area 96. The bar member 89 is secured to the bottom of the T chord 61 by welded area 93 and the bottom of the 15 bar member 90 is secured to the bar members 88 and 97 by welded area 94. This bar member 97 is an inwardly extended end extension of the bent bar, as distinguished from the outward extension 32 shown in Figures 13 and 20 38, for instance, this bar end extension being secured to the lower T chord 61 by means of welded area 95. The end web-member 91 is secured by welded area 98 to the bent bar and to the upper chord 61.

25 These figures 27 to 39, inclusive, are intended to portray some of the many modifications of chord structures and unit-end structures which may be utilized to form structural units containing the improvements of my invention.

30 What I claim is:

1. An end member for truss-like structural units comprised of a plate forming a supporting base; a strengthening plate secured to said base and extended upwardly at right angles thereto and adaptable for connection to an upper chord of a truss, said base plate being extended inwardly and downwardly at its inner end; a stress-transferring bar secured intermediate its ends to the inner end of said strengthening plate and 35 also secured to the downwardly-inclined portion of said base plate, both ends of said bar being extended downwardly and rigidly secured together at their bottom portions, said bar being formed adjacent the bottom with means adaptable for attachment to a truss chord.

2. An end member for truss-like structural units comprised of a plate forming a supporting base; a strengthening plate secured to said base and extended upwardly at right angles thereto and adaptable for connection to an upper chord of a truss, said base plate being extended inwardly and downwardly at its inner end; a stress-transferring bar rigidly secured intermediate its ends to the inner end of said strengthening plate and also secured to the downwardly-inclined portion of said base plate, both ends of said bar being extended inwardly and downwardly and rigidly secured together at their bottom portions, one of the bottom ends 50 of said bar being formed with a horizontal extension adaptable for attachment to a truss chord.

65

70

75

3. In a truss-like structural unit, the combination of top and bottom chord-members; a web-member connecting said chord-members, the latter extending at the ends beyond the ends of said web-member; reenforced unit-ends integrally connecting the adjacent chord-ends and extending outwardly thereof; and filling bars serving as end web extensions secured to the ends of the web-member, to the top and bottom chord-members, and to the reenforced unit-ends, the length and angularity of said web end extensions varying according to the span between said unit ends.

4. In a truss-like structural unit, the combination of top and bottom chord-members; a web-member connecting said chord-members, the latter extending at the ends beyond the ends of said web-member; reenforced unit ends integrally connecting the adjacent chord-ends and extending outwardly thereof and having unit-end bearing portions; and outwardly and downwardly extended end web extensions secured to the ends of the web-member, to the top and bottom chord-members, and to the reenforced unit-ends, the length and angularity of said 100 end web extensions varying according to the span between said unit ends.

5. In a truss-like structural unit, the combination of top and bottom chord-members; a web-member connecting the central portions of said 105 chord-members; end web-members connecting the respectively adjacent end portions of said chord-members and connected to the respective ends of the central web, said end webs being heavier per unit length than the central web, 110 said chord-members at the ends extending beyond the ends of said end webs; reenforced chord-end extensions secured to the top chord and forming unit-end bearing portions and having downwardly inclined extensions secured to the 115 adjacent ends of the bottom chord; and outwardly and downwardly extended end web extensions secured to the ends of the end web-members, to the top and bottom chord-members, and to the reenforced chord-end extensions. 120

6. An end member for truss-like structural units comprised of a plate forming a supporting base; a strengthening plate secured to said base and extended upwardly at right angles thereto and adaptable for connection to an upper chord 125 of a truss, said base plate being extended downwardly at its inner end; a stress-transferring bar rigidly secured intermediate its ends to the inner end of said strengthening plate, said bar being doubled upon itself for connection at a bend to 130 the upper chord of a truss, and secured to the downwardly inclined portion of said base plate, the two ends of said bar converging downwardly to a bottom joint adaptable for connection to the lower chord of a truss and having an integral 135 extended terminal member.
